UNITED STATES PATENT OFFICE.

GEORGE A. SPRATT, OF COATESVILLE, PENNSYLVANIA.

AEROPLANE.

1,394,585.

Specification of Letters Patent. Patented Oct. 25, 1921.

Application filed January 3, 1920. Serial No. 349,165.

To all whom it may concern:

Be it known that I, GEORGE A. SPRATT, a citizen of the United States, residing at Coatesville, in the county of Chester and State of Pennsylvania, have invented certain Improvements in Aeroplanes, of which the following is a specification.

My invention relates to improvements in aeroplanes, providing a system of stress distribution, whereby the weight is apportioned to a light aerofoil, in flight, in a simple and efficient manner, and, in land, is distributed to the ground through means that are efficient, flexible and safe.

The improvements of my invention are embodied in an aeroplane of stable design, in which the aerofoil is carried well above the wheel base, being a development of my invention disclosed in my U. S. application, Serial No. 252,780.

My improved aeroplane comprises a V-shaped wheel base frame provided with a forward wheel or skid at its apex and with rear wheels disposed at the rear ends of the diverging frame members, where they are attached by flexible connections; an adjustable median beam or keel extending rearwardly from the apex of the V-frame and by which the engine, propeller, tail vanes and operator are supported; an upright frame comprising struts converging from hinged connections with the rear ends of the diverging sides of the base frame, together with diverging struts extending upwardly from connections with the upper portions of the converging struts; a braced aerofoil hinged to the diverging struts and comprising a light but strong circularly arched construction having a single web sustained by sectional ribs extending in opposite directions on opposite sides thereof into lapping relation; and steering mechanism for operating the vanes and aerofoil or aerofoils.

In the drawings, Figure 1 is a front elevation of an aeroplane embodying my improvements; Fig. 2 is a perspective view of the same; Fig. 3 is a vertical sectional view taken through an aerofoil embodying my improved construction; Fig. 4 is a rear elevation of detached parts of the upright frame and the steering mechanism; Fig. 5 is a sectional side elevation of parts illustrated in Fig. 4; Fig. 6 is a sectional view taken on the line 6^x—6^x of Fig. 4; Fig. 7 is a sectional view taken on the line 7^x—7^x of

Fig. 5; Fig. 8 is a front elevation of a detached side wheel together with its yoke and connections; Fig. 9 is a top plan view of the construction shown in Fig. 8, and Fig. 10 is a fragmentary sectional view through a portion of the keel.

As illustrated in the drawings, the V-shaped base frame comprises the rearwardly diverging sides 1 and the intermediate beam or keel 2 connected at their forward ends by the pivot 3, the frame being provided at its apex with the skid 4 containing the rollers or wheels 5.

The member 2 supports the upright truss 6 which carries the engine 7 and the propeller 8; the post 9 which is connected to the keel 2 by the hinge 9' and provides a bearing for the steering mechanism; the seat 10 for the operator, and the vertical tail vane 11 having the horizontal tail vane 12 fixed thereto and braced by the cables 13 and 14.

Diagonal struts 15 converge upwardly from hinged connections 15' with the rear ends of the base members 1. Diagonal struts 17 diverge upwardly from fixed connections with the struts 15 to the hinges 18 by which they are joined to the cross braces 19 connecting the upper aerofoil 20 with the lower aerofoil 21 on either side of the median cross braces 19, the struts 17 extending through the respective openings 22 in the lower aerofoil. The aerofoils are further connected together and braced by end cross braces 19, vertical end braces 23 and tension members 24, 25 and 61.

A longitudinally disposed bar 26 is loosely connected to the top of the post 9 by the yoke 16 and fixed to the tops of the struts 15. This bar has its front end connected by the diverging cables 26' and its rear end connected by the diverging cables 27 with the tops of the struts 17. A curved guide post 28 is connected by the hinge 28' with the rear end of the bar 26 and extends through the keepers 29 on the vane 11, the post having its center in the axis of the wheels 5 and the keepers being fixed in adjustable relation to the post to permit adjustment of the vane 12 angularly to its length.

Struts 30 fixed to the lower ends of the struts 15, have fulcrumed thereon the levers 31 which are connected at their forward ends by the respective diverging cables 32 with the front spar or edge of the aerofoil 20 and at their rear ends by the respective

diverging cables 33 with the rear spar or edge of this aerofoil. Cables 61' connect the pintles of the hinges 15' on which the parts 30 bear and cables 61'' connect these 5 pintles with the hinges 18.

A sleeve 34 is adapted to rock on the post 9 and is held against longitudinal movement thereon by the pin 35, which extends through the post beyond the sleeve so as to lie under 10 the engine bed 7'. This sleeve is provided with an arm 36, which is connected by the flexible members 37 with the struts 15, and has fulcrumed thereon, by the stud 38, a lever 39 provided with the operating arm or 15 fork 40 and the work arms 41 and 42. The forward arm 41 is connected by the cable 43 with the front spar or edge and the rear arm 42 is connected by the cable 44 with the rear spar or edge of the aerofoil 21. Hence when the arm 40 is elevated the lever 20 39 will be rocked so that it will act through the cable 43 on the aerofoil 21 which will tilt the aerofoils forward. When the arm 40 is depressed, the lever 39 acts through 25 its arm 42 and the cable 44 to tilt the aerofoils in the opposite direction. When the arm 40 is rocked to the right or left, the sleeve 34 is turned on the post 9 and the arm 36 acts through the members 37 to 30 effect a relative movement between the connected frame members 1 and 15 and the keel 2 with the vanes thereon, thus deflecting the vane 11 laterally to vary the direction of flight laterally.

The circularly arched aerofoils 20 and 21 35 comprise the fabric 46 which is drawn between the spars or front and rear edges 47, to which it is fixed. Circularly arched sectional ribs 49 and 50 extend in opposite 40 directions from the spars or edges, to which they are fixed, on opposite sides of the fabric. Each rib extends say two-thirds of the distance between the spars or edges of the aerofoils so that one overlaps the other, 45 the ribs being feathered to a greater or less degree where they overlap and being secured together through the fabric. Thus the parts of the fabric primarily subject to the attack of the air is smooth and unobstructed by the 50 ribs as in usual constructions, while it is held firmly between the ribs.

The wheels 5 are journaled in frames comprising the angularly disposed yokes 51 and 52. Vertical bearings 53, fixed to the frame

member 1 by struts 53' and loosely connected to the members 15 by the links 53'', have the yokes 51 engaged thereto by the rubber coils 54, which are fixed to the respective parts 53 by the plates 55 and to the parts 51 by the plate 56, the parts 53 having 55 the end rollers or anti-friction bearings 57 for engaging the vertical yokes. The horizontal yokes 52 are loosely connected by the links 58 with bearings 60 on the frame members 1.

These wheels 5 are thus provided with means permitting them to move angularly without strain, with relation to the frame of the aeroplane when landing on irregular ground or moving laterally, while acting to 70 right them so that they are restored to normal position.

The foregoing construction is relatively light, flexible and thoroughly braced.

Having described my invention, I claim: 75

1. In an aeroplane, the combination with a frame of an aerofoil having spars, of a circularly arched fabric drawn between said spars, and ribs extending oppositely from said spars on opposite sides of said fabric 80 into overlapping relation, said ribs being shorter than the distance between said spars.

2. In an aeroplane, an aerofoil having spars, a fabric extending between said spars and ribs extending in opposite directions 85 from said spars on opposite sides of said fabric into lapping relation, the length of said ribs being substantially less than the distance between said spars.

3. In an aeroplane, a circularly arched 90 aerofoil comprising a fabric and ribs extending in opposite directions on the opposite sides of said fabric from the forward and rear edges thereof, the lengths of said ribs being substantially less than the distance between said edges.

4. In an aeroplane, the combination with a frame, of a pair of aerofoils having connecting members hinged to said frame, said aerofoils having respectively front and 100 back fixed to said connecting members and overlapping ribs extending from each spar toward the other.

In testimony whereof I have hereunto set my hand, this 29th day of December, 105 1919.

GEO. A. SPRATT.
